PUSHER FOR USE IN IMPLANTING PROSTHESIS IN TOTAL KNEE ORTHOPEDIC PROCEDURE

Robert T. Rylee II, 411 N. 3rd at Parkway,
Memphis, Tenn. 38105

Filed Feb. 14, 1973, Ser. No. 332,252

Term of patent 14 years

Int. Cl. D24—02

U.S. Cl. D83—12 R

The single figure of the drawings is a perspective view of the pusher for use in implanting prosthesis in total knee orthopedic procedure, the rear view being identical to FIG. 1.

I claim:

The ornamental design of a pusher for use in implanting prosthesis in total knee orthopedic procedure, as shown and described.
